SEGREGATION OF XYLENE ISOMERS

Edward M. Geiser, Downers Grove, Ill., assignor, by
mesne assignments, to Universal Oil Products Company,
Des Plaines, Ill., a corporation of Delaware

No Drawing. Filed Nov. 5, 1957, Ser. No. 694,505

6 Claims. (Cl. 202—39.5)

This invention relates to a process for the separation and recovery of one or more xylene isomers from a hydrocarbon mixture containing the same, utilizing certain classes of amides as solvents for the selective extraction of one of the particular isomers in the mixture. More specifically, this invention concerns an extraction process for segregating the components of a C_8 aromatic hydrocarbon-containing mixture, utilizing an N-substituted alkyl amide as selective solvent for the extraction of one of the C_8 aromatic isomers.

In one of its embodiments this invention relates to a process for the selective separation of a particular xylene isomer from a hydrocarbon mixture comprising C_8 aromatic hydrocarbons which comprises contacting said mixture with a solvent comprising an N-alkyl carboxamide while maintaining said amide in substantially liquid phase to thereby form a rich solvent stream comprising at least one of the xylene isomers present in said mixture dissolved in the solvent and a separate raffinate phase comprising at least one other of the xylene isomers present in said mixture in a proportion greater than its proportion in the mixture and thereafter separating the raffinate phase from the rich solvent stream.

A more specific embodiment of the foregoing process comprises separating at least one of the group selected from ethylbenzene and para-xylene from a hydrocarbon mixture comprising C_8 aromatic hydrocarbon isomers, said process comprising: distilling said hydrocarbon mixture in the presence of dimethylformamide, countercurrently contacting the resulting hydrocarbon vapors with a liquid solvent comprising dimethylformamide and separating an overhead stream comprising a hydrocarbon portion enriched with one of the isomers selected from the group consisting of ethylbenzene and para-xylene.

Charging stocks which may be utilized in the present separation process include generally hydrocarbon mixtures containing either exclusively aromatic components or these may be accompanied by other classes of hydrocarbons, such as paraffins, other aromatics, olefins, naphthenes, etc., although preferably, the present separation process is most effectively utilized with a feed stock from which the non- C_8 aromatic hydrocarbon components are eliminated or in which these components constitute a minor proportion of the whole. One of the preferred feed stocks for use herein is a fraction boiling within the range of from about 120° to about 160° C. which may be derived from certain petroleum conversion products containing aromatic hydrocarbons and more particularly, the aromatic hydrocarbons of C_8 composition. The isomeric xylenes are particularly predominant in certain gasoline boiling range fractions of petroleum conversion products, such as the product of a reforming process in which aliphatic and naphthenic hydrocarbons undergo dehydrogenation, isomerization and/or cyclization reactions to form their corresponding aromatic analogs. The desired fraction particularly selected for charging stock in the present process may contain, for example, two or more of the C_8 aromatic isomers, in-

2

cluding, ortho-xylene (having a boiling point of 144° C. at 760 mm. pressure), meta-xylene (having a boiling point of 138° C. at atmospheric pressure), para-xylene (boiling point: 138° C. at 760 mm.) and ethyl benzene (boiling point: 136.2° C. at 760 mm.). The fraction of such a conversion product, boiling within the range of from about 120° to about 145° C., would contain substantially all of the various C_8 isomers, including azeotropes thereof with other classes of hydrocarbons which may also be present in such a fraction.

According to the present separation process, a hydrocarbon mixture containing at least two xylene isomers is contacted, preferably under countercurrent flow conditions with a solvent extractant characterized as an N-alkyl carboxamide under contacting conditions of temperature and pressure that at least one of the fluid phases present in the contacting chamber is in substantially liquid state. The carboxamides herein utilized as solvent-extractants are compounds having the following empirical formula:

wherein R and R_1 are selected from the group consisting of hydrogen and alkyl and R_2 is selected solely from alkyl, each of said alkyl radicals containing from one to four carbon atoms. The preferred members of the above group of carboxamides utilized herein as solvent-extractants are compounds which are relatively volatile and which boil approximately at or below the boiling point of the hydrocarbon mixture supplied to the extraction zone as the charge stock. Thus, the preferred compounds having these volatility characteristics are members of the above group in which the total number of carbon atoms in the groups: R, R_1 and R_2 does not exceed about five in number. Particularly preferred herein, especially for a process involving extractive distillation of the hydrocarbon charge stock are the mono- and di-methyl and mono- and diethyl formamides and acetamides; that is, compounds in which the R, R_1 and R_2 groups are hydrogen, methyl or ethyl. These compounds are sufficiently volatile to distill over at least in part with the isomer comprising the overhead, and yet have sufficiently high boiling points to provide a liquid solvent phase in the extractive distillation column during the fractionation of a mixture of the carboxamide with the charge stock. It is to be emphasized that all of the members of the above general class of compounds do not produce equivalent results and although all are at least somewhat effective in separating a C_8 aromatic hydrocarbon isomer from a mixture thereof with other C_8 aromatic hydrocarbons, the members of the above group in which the R substituents in the structure of the compound are hydrogen, methyl or ethyl are generally preferred.

The present N-alkyl carboxamide extractants may be utilized as selective solvents in any conventional system of extraction involving contact between the amide solvent, generally supplied in liquid phase, and the mixed hydrocarbon feed stock in liquid or vapor state. Thus, the solvent may be countercurrently contacted with the hydrocarbon feed stock in a countercurrent-liquid-liquid solvent extraction zone, for example utilizing an absorption type separation procedure wherein the amide solvent as the phase of greatest density is introduced into the upper portion of a suitable liquid-liquid contacting zone and the hydrocarbon feed stock as the phase of lesser density is introduced into the bottom portion of the contacting zone, the resulting streams being allowed thereafter to flow in countercurrent contact with each other. A so-called "rich solvent" stream containing as a solute

the component of the feed stock of greatest solubility in the solvent, generally ortho- and/or meta-xylene, if present in the hydrocarbon charge, is removed from the lower portion of the extraction zone, while the non-extracted portion of the charge stock, normally referred to as the "raffinate" phase, is removed from the upper portion of the contacting zone. Provided a sufficient volume of solvent is charged into the contacting zone, compared to the volume of charge stock, the rich solvent stream may contain substantially all of the meta-xylene and ortho-xylene components of feed stock, if present therein. Similarly, the raffinate stream is composed predominantly of the relatively insoluble components of the charge stock and if a sufficient number of contacting stages is provided in the extraction zone, the raffinate may consist substantially completely of ethyl benzene. The para-xylene component, when present, may be recovered from the extraction zone of the latter type from a plate located at an intermediate point between the raffinate and extract outlets as a side stream therefrom. In order to provide a cyclic process in which the solvent is recirculated to the contacting zone after removing extracted C₈ isomer therefrom, the rich solvent stream may be separately treated, from example, by subjecting it to fractional distillation (the so-called stripping method of the prior art) in order to recover the extract hydrocarbon therefrom as a vapor overhead substantially enriched in ortho-xylene. In such a stripping operation the rich solvent is heated to a temperature above the boiling point of the dissolved hydrocarbon in the presence of the solvent and at the particular pressure maintained in the stripping zone, the solute vapors flash overhead from the rich solvent and collect as a liquid condensate in the receiver vessel. The residue remaining in the bottom of the stripping column generally consists of substantially regenerated lean solvent which may thereafter be recirculated to the contacting or solvent extraction zone for reuse therein.

Another means of utilizing the present N-alkyl carboxamide solvents in an extraction procedure comprises introducing the solvent, which may be an aqueous mixture of the same, at a suitable solvent extraction temperature, preferably at least about 20° above the end boiling point of the charge stock into an extractive distillation zone into which the feed stock as a heated liquid or as a vapor is also simultaneously introduced, the resulting extractive distillation forming a liquid phase, rich solvent as a separate stream from the raffinate phase recovered from the extractive distillation zone as an overhead vapor.

In most instances the alkyl amides herein specified for use as solvent extractants have boiling points substantially above the boiling point of the charge stock and the maintenance of at least a portion of the solvent in liquid phase can therefore be effected at atmospheric pressure or at a relatively small superatmospheric pressure. In other instances, that is, when the molecular weight of the carboxamide is sufficient to predetermine its boiling point at a relatively high level, it becomes expedient to dilute the carboxamide with water or a lower boiling organic compound to thereby reduce the temperature at which extractive distillation will take place. In most instances, however, the solvent component utilized in any particular process should not exceed about 50% by weight of the total composition because of the substantial reduction in the solubility relationships for the hydrocarbon charge stock as the proportion of water or other solvent in the composition increases.

For the extraction of charge stocks boiling above about 110° C., below about 175° C., thereby including all known azeotropic hydrocarbon mixture with any of the xylene isomers, the extraction temperature (that is, the temperature at which the solvent composition contacts the charge stock) is preferably in an excess of about 87° C. but not substantially greater than 200° C., the required pressure at these temperatures varying in accordance with

the boiling point of the feed stock and the solvent composition utilized in the process. In general, pressures of from atmospheric to 20 atmospheres or higher are sufficient to maintain at least a portion of the solvent composition in liquid phase during the course of the extraction. In an extractive distillation type of separation procedure (in general, one of the preferred methods of separation for use in the present process), the boiling point of the aliphatic components in the charge stock (if present) are affected least by the presence of the solvent and any aliphatic components in the charge stock, therefore, tend to distill overhead from the extractive distillation zone at approximately the normal boiling point of the particular aliphatic components present in the mixture or at the boiling point of a constant boiling mixture thereof with other aliphatic components present in the mixture. The most volatile portion of the overhead distillate is generally the aliphatic components in the charge stock and in a batch distillation, these are collected and segregated first from the overhead. A higher boiling cut may thereafter be distilled overhead, the fraction thus collected containing a greater proportion of ethylbenzene (if present in the charge stock) than the other xylene isomers. The next fraction which boils at a slightly higher temperature than the previous cut contains a greater proportion of the para-xylene isomer (if present in the charge stock); hence, the next highest boiling cut contains a greater proportion of para-xylene than is present in the charge stock. As successively higher boiling cuts are removed from the extractive distillation zone in the presence of the carboxamide solvent, meta-xylene and thereafter, ortho-xylene, distills overhead, depending upon the boiling point of the solvent composition. Each of the resulting enriched cuts (enriched, that is, with respect to the individual isomer which predominates in the particular cut) may thereafter be redistilled in the presence of the solvent to effect greater purification of the particular isomer predominating in the cut. Although the foregoing batch-type extractive distillation procedure may be utilized for any given charge stock and any given solvent composition, a continuous process involving a multi-stage extractive distillation procedure, effected in a series of distillation columns each having more than two and preferably more than ten theoretical plates may be provided; for this purpose a separate column is provided for each isomer taken overhead in the succession of columns, the bottoms of one column being transferred as feed into the next succeeding distillation column for separation of the next higher boiling isomer. Such a procedure comprises a particularly preferred arrangement for continuously separating a multi-isomer containing hydrocarbon mixture.

The present extractive distillation process involves the continuous separation of an overhead distillate, which, after condensation, separates into two liquid phases: (1) a fraction comprises predominately hydrocarbon enriched with respect to one of the isomers (depending upon the boiling point of the distillate) and in which a relatively minor amount of solvent is dissolved, and (2) a second liquid phase consisting predominantly of solvent in which a relatively minor amount of hydrocarbon may be dissolved and which, in the case of utilizing an aqueous carboxamide solvent composition, may contain a larger proportion of water than is present in the solvent composition charged to the separation zone. In a preferred manner of operating the present process the layer separating from the condensed overhead consisting predominantly of solvent components is refluxed at least in part to one of the upper trays of the extractive distillation column, thereby providing a descending lean solvent stream which enhances the extractive distillation of the feed stock; alternatively, the solvent layer may be redistilled in a separate column to separate the solvent components and any hydrocarbon which may be present therein for recycle of the solvent constituents in the proc-

ess. The hydrocarbon layer separated from the overhead distillate of the extractive distillation column is substantially enriched in one of the desired xylene isomers and, as indicated above, may contain relatively minor amounts of the solvent composition dissolved therein. In order to recover the solvent constituents, the hydrocarbon layer may be redistilled, thereby effecting a secondary fractionation of the hydrocarbon components, leaving a residue consisting predominantly of previously dissolved solvent which may be recycled to the extractive distillation stage. In order to recover the minor amount of solvent in the hydrocarbon layer, the latter may also be washed with a stream of water, preferably under countercurrent flow conditions, to extract the dissolved solvent components therefrom.

The present invention is further illustrated with respect to several of its specific embodiments in the following illustrious examples, which however, are not intended to necessarily define the scope of the invention in accordance therewith.

In the following series of runs a mixture of C_8 aromatic hydrocarbons comprising the various isomers of xylene are distilled (1) individually (that is, without the presence

TABLE I
Distillation of mixed C_8 aromatic hydrocarbon isomers

p-Xylene/m-Xylene	0.42	0.46	0.46	0.43	0.33	0.34	

The above data indicate that a slight enrichment of the para-xylene was obtained in the first fractions distilled overhead, but the ratio of isomer enrichment is relatively minor.

In the following run, 75 cc. of di-methyl formamide was mixed with the 150 cc. of xylene isomer charge stock, followed by distillation in the same column as that utilized in the foregoing runs in which the distillation was effected in the absence of non-hydrocarbon entrainers.

of non-hydrocarbon components), (2) with di-methyl formamide under azeotropic conditions, and (3) with an aqueous solution of di-methyl formamide under azeotropic distillation conditions. The distillates were separately collected in various cuts, determined by the boiling point of the cut and the constancy of the boiling point, after which the composition of the hydrocarbon layer (if phase separation takes place in the distillate) was determined by infra-red analysis, noting particularly the distribution of isomers in each of the cuts and comparing the composition of these cuts with the corresponding cuts separated by distillation of the C_8 aromatic charge stock in the absence of non-hydrocarbon components.

In order to determine the distribution of xylene isomers in the distillate fractions separated by distillation of the C_8 aromatic charge stock in the absence of non-hydrocarbon entrainers, a charge stock consisting of a mixture of xylene isomers of reagent grade quality is utilized, the feed stock containing the following components in their indicated proportions by weight:

Toluene	0.2
Ethylbenzene	5.5
p-Xylene	27.0
m-Xylene	64.3
o-Xylene	3.0
p-Xylene/m-Xylene	0.42

The above mixture of isomers was charged into the distillation flask attached to a fractional distillation column of three foot length packed with glass helices. The distillation provided the data indicated in the following Table I.

The data in the above table indicate that the para-xylene and ethylbenzene components of the charge stock tend to concentrate in the initial lowest boiling azeotropic fractions with dimethylformamide distilled from the mixture and that ortho-xylene tends to predominate in the higher boiling cuts. The data further indicate the feasibility of separating C_8 aromatic hydrocarbon mixtures employing a multi-stage fractionating column having sufficient reflux of dimethylformamide to produce a continuous countercurrent, downwardly flowing stream of solvent through the fractionating column.

In the following run, to the 150 cc. of mixed xylene isomer charge stock was added 75 cc. of dimethylformamide and 75 cc. of water, followed by azeotropic distillation of the resulting mixture. Analysis of the charge stock and the observed data involved in the distillation are reported in the following Table III.

The above data indicate the desirability of utilizing an aqueous mixture of an dialkylformamide as the extractive solvent, indicating the substantial enrichment of para-xylene (compared to meta-xylene) in the initial overhead cuts from the distillation column.

The use of other dialkyl and monoalkylformamides as well as other mono and dialkyl alkanoic amides which are less soluble in water, but relatively more soluble in the hydrocarbon charge stock indicates that both N-monoalkyl and N,N' dialkylamides may be employed as azeotroping agents. These results further indicate that alkanoic acid amides in which the alkyl group attached to the carbonyl group contains up to 5 carbon atoms may similarly be employed as separating agents in the extractive distillation of mixed xylene isomers.

When the number of carbon atoms in the carboxamide is greater than about 6, it is noted that the solubility of the amide in the xylene mixture also substantially increases and the boiling point of the amide increases with increasing molecular weight. The above results indicate that the relatively lower molecular weight carboxamides are preferred herein, because of their desirable lower volatility in the extractive distillation.

I claim as my invention:

1. A process for separating at least one isomer selected from the group consisting of ethylbenzene and para-xylene from a liquid mixture thereof with at least one other C₈ aromatic hydrocarbon, which comprises distilling said liquid mixture in the presence of a carboxamide of the formula

wherein R and R₁ are selected from the group consisting of hydrogen and an alkyl group of from one to four carbon atoms and R₂ is an alkyl group of from one to four carbon atoms, countercurrently contacting the resultant hydrocarbon vapors with said carboxamide in liquid form, and removing from the distilling and contacting steps an overhead vapor comprising a hydrocarbon portion enriched with one of the isomers selected

20 from the group consisting of ethylbenzene and para-xylene.

2. The process of claim 1 further characterized in that the total number of carbon atoms in R, R₁ and R₂ in said formula does not exceed five.

25 3. The process of claim 2 further characterized in that said carboxamide is selected from the group consisting of mono- and di-methyl and mono- and di-ethyl formamide.

4. The process of claim 1 further characterized in that said carboxamide is dimethylformamide.

5. The process of claim 4 further characterized in that said dimethylformamide is an aqueous solution.

6. The process of claim 1 further characterized in that said carboxamide is N,N-diethylformamide.
